JOHN E. TABER, OF FALL RIVER, MASSACHUSETTS.

Letters Patent No. 63,578, dated April 2, 1867.

IMPROVED SINK TRAP.

The Schedule referred to in these Letters Patent and making part of the same.

TO ALL WHOM IT MAY CONCERN:

Be it known that I, JOHN E. TABER, of Fall River, in the county of Bristol, and State of Massachusetts, have invented a new and useful Improvement in Sink or Water Traps; and I do hereby declare that the following is a full, clear, and exact description thereof.

The object of my invention is to provide a safeguard against the impure air, vapors, and stenches which rise from sink-spouts, cess-pools, or water-closets, and also to prevent the evaporation of liquids where they are exposed to the atmosphere; and the invention consists in forming a funnel-shaped valve composed of two or more pieces, which shall allow liquids to pass through, but which shall be closed, when it is empty, either by its own weight or gravity.

To enable others skilled in the art to make and use my invention, I will proceed to describe its construction and operation, reference being had to the accompanying drawings, forming a part of this specification, and to the letters of reference marked thereon.

Figure 1 represents the trap open.

Figure 2 represents it closed. They are both vertical sections of the trap as when it is in use.

Figures 3 and 4 are top views of the trap, fig. 3 showing the holes by which it may be fastened to a wooden-bottom sink. The mark *b* indicates the joint between the two portions of the valve B B.

Similar letters of reference indicate like parts.

A is a tapering band or ring with a broad flange or rim, C, around the top. This flange rests on the bottom of the sink or in the pipe, or in any position where it can be effective. The shape of A is indicated by dotted lines in figs. 1 and 2. *a* represents packing rings under the flange C. The valve, represented in the drawing in two pieces, is hung or suspended on pivots to A in such a manner that they will close or come together by their own weight when empty. Being hung so that the parts of the valve are suspended from near the centre, the larger diameter of the upper portion of the funnel acts on a weight to throw the points together, as seen in fig. 2. The portions of the valve B B are formed to any required taper, each being half a funnel, and when closed the joint *b* forms a line at right angles with the top of the trap, but the flange C of the trap may stand at any angle to suit circumstances.

The design and operation is, that liquids and other substances which will pass through will force the valve open by their weight or gravity and fall below, and that when such liquids or substances leave the valve it will immediately close, preventing all gases and noxious effluvia from ascending.

I do not confine myself to forming the valve of two pieces only. It may be formed of more than two pieces and operate satisfactorily, but it would make more joints, and I have found two pieces to be sufficient; neither do I confine myself to any particular use or application of my trap. It may be applied to cess-pools and water-closets, as well as to common sinks, and other purposes; or even as a steam trap to discharge the water of condensation from the steam cylinder. It can also be applied to an open vessel so as to admit volatile liquids but prevent their evaporation.

Having thus described my invention, what I claim as new, and desire to secure by Letters Patent, is—

The valve consisting of the two equally divided jaws B, forming a cone, their joint being at right angles with the top of the trap, pivoted at their upper inner ends thereto, whereby they close by their own gravity, substantially as described for the purpose specified.

JOHN E. TABER.
